UNITED STATES PATENT OFFICE.

HERMAN L. WAGNER, OF MOUNT VERNON, NEW YORK, ASSIGNOR TO UNDERWOOD TYPE-WRITER COMPANY, OF NEW YORK, N. Y., A CORPORATION OF NEW JERSEY.

TYPE-WRITING MACHINE.

No. 866,097.

Specification of Letters Patent.

Patented Sept. 17, 1907.

Application filed June 26, 1907. Serial No. 380,859.

To all whom it may concern:

Be it known that I, HERMAN L. WAGNER, a citizen of the United States, residing in Mount Vernon, in the county of Westchester and State of New York, have invented certain new and useful Improvements in Type-Writing Machines, of which the following is a specification.

This invention relates to the paper-guiding or feeding devices of typewriting machines, and particularly to paper-pressing rolls, and means for releasing the same.

The object of the invention is to provide simple and inexpensive means which can readily be applied to existing machines for releasing the pressure rolls.

In the accompanying drawings, Figure 1 is a front elevation of the carriage of an Underwood typewriting machine, showing my improvements applied thereto. Fig. 2 is an inverted plan showing diagrammatically the system of pressure rolls which run upon the platen. Fig. 3 is a sectional end elevation, showing the parts in working positions. Fig. 4 is a view similar to Fig. 3 but showing the pressure rolls released from the platen. Fig. 5 is a perspective view showing a portion of the pressure roll system.

Types 1 strike against the front side of a platen 2, which is mounted by means of an axle 3 in the ends 4 of a platen frame, said ends being connected by a paper shelf 5. A set of rear pressure rolls 6 is journaled upon a shaft 7, the rolls being separated by sleeves or spacers 8 fitting loosely upon the shaft. A set of front pressure rolls 9 is mounted upon a shaft 10, both shafts extending parallel with the platen axle 3. A parallel rod 11 extends from one platen frame end 4 to the other between the shafts 7, 10, and is usually fixed to said ends and forms a tie-rod for the platen frame, and usually carries a wheel 12 upon which the platen frame runs. Arms 13, 14 extend rearwardly and forwardly from said rod 11 to engage and support the roll shafts 7, 10, said arms having open ends or bearings 15 to permit ready detachment of the roll shafts and rolls bodily from the machine. Springs 16 are fixed upon the main rod 11 and press said arms, shafts and rolls toward the platen. Pendent from the main rod 11 are brackets 17, in which is journaled a rock shaft 18 having diametrical flats or cam surfaces 19, which are formed by cutting recesses 20 at intervals in the rock shaft. Yokes, straps or stirrups 22, 23 have open vertical slots 21 which fit loosely upon both said rock shaft and said rod 11. Fingers 22, 23 extend oppositely from the body of each of said yokes, and are inserted between the roll shafts and the platen. Normally the bottoms or ends of the yokes occupy the recesses in the rock shaft 18, as seen at Figs. 1 and 3; but upon depression of a release key 24, which is connected by a link 25 to a crank arm 26 on the rock shaft 18, the latter is rocked to the Fig. 4 position, thereby camming down the yokes and drawing down the roll

shafts 7, 10 and pressure rolls from the platen, to release the paper. This is done against the tension of the springs 16. The rock shaft 18 preferably turns enough to cause the yoke to engage the cylindrical surface thereof, to lock the yokes down, so that both hands of the operator are left free to manipulate the paper, the pressure rolls being mechanically held away from the platen. Upon pulling the key up again, the springs 16 restore all parts to the normal Fig. 3 positions, in which the rolls are all pressed forcibly against the platen. 65 The fingers 22 may press either directly upon the spacing sleeves 8, or directly against the shaft 7, the latter construction being illustrated in the drawings, slots being cut in the sleeves at 27 for this purpose.

When it is desired to detach either roll shaft together with its rolls, it is only necessary to pull down the pressure arms 13 or 14, as the case may be, and lift the shaft out of the open portions 15; the yokes 20 forming no impediment to this operation, since their fingers 22, 23 merely extend between the roll shafts and the platen, 75 and do not interfere with a movement of the roll shafts away from the platen. Either set of rolls may be omitted if desired, in some cases.

Having thus described my invention, I claim:

1. In a typewriting machine provided with a platen and a platen frame, the combination with two sets of rolls running upon the platen, one set in advance of the other, two spring-pressed shafts whereon the rolls are mounted, and pivoted arms for supporting the roll shafts, of a rock-shaft connected to a key and having cams thereon, and a plurality of yokes extending from said rock shaft to said roll-shafts and engageable by said cams to draw said roll-shafts and rolls from the platen. 80

2. In a typewriting machine provided with a platen and a platen frame, the combination of two sets of rolls running upon the platen, one in advance of the other, two shafts whereon the rolls are mounted, a rod mounted upon the platen frame between said sets of rolls, arms pivoted upon said rod and supporting the roll shafts, springs pressing the shafts towards the platen, a rock shaft connected to a key and having cams thereon, and a plurality of yokes extending from said rock-shaft and movable by said cams away from the platen and having means to draw said roll shafts and rolls from the platen against the tension of said springs. 90

3. In a typewriting machine provided with a platen and a platen frame, the combination of two sets of rolls running upon the platen, one in advance of the other, two shafts whereon the rolls are mounted, a rod mounted upon the platen frame between said sets of rolls, arms pivoted upon said rod and supporting the roll shafts, springs pressing the shafts towards the platen, a rock shaft connected to a key and having cams thereon, and a plurality of yokes having slots whereby they are guided by said rock shaft and said rod, said yokes extending to said roll shafts 105 and engageable by said cams to draw said roll shafts and rolls from the platen against the tension of said springs. 110

4. In a typewriting machine provided with a platen and a platen frame, the combination of two sets of rolls running upon the platen, one in advance of the other, two shafts whereon the rolls are mounted, a rod mounted upon the platen frame between said sets of rolls, arms pivoted 115

- upon said rod and supporting the roll shafts, springs 35
pressing the shafts towards the platen, a rock shaft connected to a key and having cams thereon, and a plurality of yokes having slots whereby they are guided by said rock
5 shaft and said rod, said yokes extending to said roll shafts and engageable by said cams to draw said roll shafts and rolls from the platen against the tension of said springs, each yoke having oppositely extending fingers inserted between the rock-shafts and the platen, to effect the release
10 of the rolls.
5. In a typewriting machine provided with a platen and a platen frame, the combination with two sets of rolls running upon the platen, one set in advance of the other, two 40
15 spring-pressed shafts whereon the rolls are mounted, and pivoted arms for supporting the roll shafts, of a rock-shaft connected to a key and having cams thereon, and a plurality of yokes extending from said rock shaft to said roll-shafts and engageable by said cams to draw said roll-shafts and rolls from the platen; said roll-shafts and rolls being 45
20 bodily detachable from the machine independently of said yokes.
6. In a typewriting machine provided with a platen and a platen frame, the combination of two sets of rolls running upon the platen, one in advance of the other, two 50
25 shafts whereon the rolls are mounted, a rod mounted upon the platen frame between said sets of rolls, arms pivoted upon said rod and supporting the roll shafts, springs 55
30 pressing the shafts towards the platen, a rock shaft connected to a key and having cams thereon, and a plurality of yokes having slots whereby they are guided by said rock shaft and said rod, said yokes extending to said roll shafts and engageable by said cams to draw said roll shafts and rolls from the platen against the tension of said springs.
- each yoke having oppositely extending fingers inserted between the rock-shafts and the platen, to effect the release 35
of the rolls, and said arms having open bearings for the roll shafts, the latter being detachable from the machine independently of said yokes.
7. In a typewriting machine provided with a platen and a platen frame, the combination with a roll running upon the platen, and a shaft for said roll, of a rod fixed in the platen frame, pivoted arms extending from said rod to guide said shaft, a rock shaft mounted in the platen frame and connected to a key, and yokes or stirrups each slotted 40
45 thereon and having a finger inserted between the roll shaft and the platen, to engage the roll shaft; said rock shaft having cam portions thereon to engage said yokes to draw the roll shafts away from the platen.
8. In a typewriting machine provided with a platen and a platen frame, the combination with a roll running upon the platen, and a shaft for said roll, of a rod fixed in the platen frame, pivoted arms extending from said rod and having at their ends open bearings to guide said shaft, a 50
55 rock shaft mounted in the platen frame and connected to a key, and detachable yokes or stirrups having open slots to engage both said rock shaft and said rod to be guided thereon, and having fingers inserted between the roll shaft and the platen, to engage the roll shaft; said rock shaft having cam portions thereon to engage said yokes to draw the roll shaft away from the platen, and said roll shaft being detachable independently of said yokes.

HIERMAN L. WAGNER.
